UNITED STATES PATENT OFFICE.

LEE P. HYNES, OF CHICAGO, ILLINOIS, ASSIGNOR TO THERMO ELECTRIC REGULATOR CO., OF CHICAGO, ILLINOIS, A CORPORATION OF ILLINOIS.

RESISTANCE UNIT.

1,297,472.

Specification of Letters Patent. Patented Mar. 18, 1919.

Application filed May 7, 1915. Serial No. 26,482.

To all whom it may concern:

Be it known that I, LEE P. HYNES, a citizen of the United States of America, and resident of Chicago, Cook county, Illinois, present res. add., 7320 Princeton ave., have invented a certain new and useful Improvement in Resistance Units, of which the following is a specification.

My invention relates to resistance for use in electrical circuits, and more particularly to devices of this kind which are designed to be employed in exposed positions, as in making uncovered connections for circuits employing heavy and dangerous currents, and which must, therefore, be suitably protected or covered.

Generally stated, the object of my invention is to provide a comparatively simple and inexpensive resistance unit of the foregoing general character, and to provide a device of this kind which will be satisfactory and reliable in use, as well as safe to employ in exposed places.

A special object is to provide an improved construction and arrangement whereby a resistance unit of this general character may be produced at a comparatively small cost of manufacture.

It is also an object to provide certain details and features of construction tending to increase the general efficiency and desirability of a resistance device of this particular character, not only from the standpoint of actual use, but also with regard to the satisfactory and low cost of production thereof.

To these and other useful ends my invention consists in matters hereinafter set forth and claimed.

40 In the accompanying drawings—

Figure 1 is a longitudinal section of a resistance unit embodying the principles of my invention.

Fig. 2 is an end view of the device shown in Fig. 1.

Fig. 3 is a cross section on line 3—3 in Fig. 1.

As thus illustrated, my invention comprises a tube A of porcelain or similar insulating material, having opposite ends a of any suitable shape. The resistance coil B is wound on said tube and then coated with enamel C or other similar heat resisting and insulating material. This holds the coil firmly in place. For example, the tube A

can be of hard baked or fired clay or pottery, and may have the enamel C baked and vitrified thereon by any well known method. Thus the coil B is suitably insulated and embedded in the vitreous enamel coating of 60 the tube. Heads D of insulating and heat resisting material are provided with cylindric recesses d to receive the ends of said tube A, these heads being of cylindric form and having axial holes E which communicate with the bore of said tube. Any substance may be used for these heads D, such as some of the white vitreous insulation, or asbestos preparations, or other similar substances, commonly used in the manufacture 70 of electrical articles. A perforated sheet metal cylinder F is arranged to inclose the resistance coil and extend over said heads D, the end edges of said cylinder being bent inward to form flanges f which hold the heads 75 against outward displacement. Said cylinder F is preferably formed from sheet metal and has a lap joint G along one side thereof. The terminals b of the coil extend around and into the ends of the tube A, washers H 80 of asbestos wicking being interposed between the ends of said tube and the heads. Conductors I of strand wire are covered with asbestos insulation i and arranged to extend through the holes E and into said 85 tube. Knots J are formed in these flexible conductors immediately inside the washers H, and the terminals b are electrically united with the ends of said conductors inside of said knots. Thus the pull is on the knots J, 90 when the device is connected up or used, and not on the terminals b of the coil.

If desired, the cage F may have interior beads f extending circumferentially thereof immediately inside of the heads D, thus 95 preventing the latter from being pushed inward. The said cage constitutes the sole means for holding said heads D in place on the ends of the resistance tube, and the washers H serve to cushion and protect the 100 ends of said tube against breakage. In this way the heads D are not connected by any thing extending through the tube A, and thus danger of short circuiting is greatly reduced.

For the broader purposes of my invention any suitable resistance may be inclosed within the cage F and held in place by said heads. But the form of resistance coil shown and described is suitable for the pur- 105 110

pose, and in such case the brittle and breakable tube A is preferably cushioned in the heads to prevent breakage during manufacture and afterward as well. Also, the heads D and cage F may be of any suitable or desired shape.

As shown, the washers H are cup-shaped to effectually surround the ends of the fragile tube A and thereby prevent breakage when the device is subjected to shock or jar. The washers can be molded or made in this shape, or they can be made flat and soft and allowed to flow out at their edges when the two heads D are brought toward each other. 15 But these washers can be of any suitable shape and character.

I do not limit myself to the exact construction shown and described.

What I claim as my invention is:—

20 1. A resistance unit comprising a resistance element, insulating heads for the opposite ends of the resistance element, connections extending through said heads to the resistance, and a foraminous cage having means to hold said heads in place, said cage being spaced from said element, said element comprising a breakable tube, and means for cushioning the ends of said tube in the heads, said cage preventing both inward and outward displacement of said heads.

2. A resistance unit comprising a tubular

resistance element, heads for the resistance element, means to connect said heads, and means to cushion the ends of said element in said heads, said cushioning means comprising cup-shaped washers on the ends of said element, said heads being cup-shaped to hold said washers, and conductors extending through said washers and connected with adjacent ends of said element.

3. A resistance unit comprising oppositely arranged cup-shaped heads of insulation, a tubular resistance-element having its ends disposed in said cup-shaped heads, said element involving an outer coil and an inner tube of heat-resisting insulation, said heads having means to cushion the ends of said tube therein, insulated conductors extending centrally through said heads and into the ends of said tube, each conductor being connected with the adjacent end of said coil, and a cylindric cage having openings in the sides thereof and provided with end portions which extend beyond said heads, these end portions of the cage having integral means to hold the heads against both inward and outward displacement, and to render removal of said heads impossible except by forcibly bending the metal of the cage at the extreme ends thereof.

Signed by me at Chicago, Illinois, this 24th day of April, 1915.

LEE P. HYNES.
